AIRCRAFT, ESPECIALLY AIRCRAFT OF THE AMPHIBIAN TYPE AND BODY BOAT STRUCTURE FOR SAME

Application filed December 30, 1929. Serial No. 417,563.

The present invention relates to amphibian aircraft and particularly to details of body boat or hull structure. The purpose of the invention is to provide a specific rib arrangement whereby lifting and landing stresses may be distributed to the body boat outside of the localized point of attachment of the lifting and landing adjuncts.

The invention will be described with reference to the accompanying drawings, in which

Figure 1 is a perspective of an amphibian.

Figure 2 is a side elevation of the amphibian with parts broken away, and

Figure 3 is an enlarged side elevation of a portion of the amphibian with parts removed or broken away.

Referring to the drawings, reference numeral 5 indicates the body boat or hull of the amphibian above and transversely of which extends a main plane 6. Lower wings 7 and 8 project laterally of the body boat and are secured thereto intermediate its top and bottom. Extending rearwardly of the main plane are a pair of outriggers 9 and 10, which support an empennage assembly generally indicated at 11.

A retractable landing wheel is provided at each side of the body boat, the one at the left alone being shown and being retained at 12. The wheel 12 is mounted on an axle 13 swingable about a horizontal axis and having secured to its free end a rod 14 provided at its upper end with a piston working in a cylinder enclosed in the fairing 15. The upper end of the cylinder is pivoted to the lower end of a rigid upright 16 which at its upper end is secured to the front spar 17, Figure 2, of the main plane.

Fluid is adapted to be admitted into the cylinder at either side of the piston head secured to rod 14 to reciprocate the latter and thereby swing the wheel from operative to inoperative position or vice versa. The pivotal connection of the cylinder with upright 16 permits the former to swing in a plane across the body boat so as to accommodate the swinging of axle 13.

The body boat structure, so far as the present invention is concerned, comprises a series

of ribs converging upwardly at points of attachment of lifting and landing members to the body boat. In Figure 3, the reference numerals 18 and 19 designate attachment brackets for the left wing 8. Converging at bracket 18 are a series of ribs 20, 21, 22 and 23, all of which are secured to the body boat sheathing and at their converging ends to bracket 18. The lower end of rib 20 is secured to a futtock 24 and the lower ends of ribs 21 to 23 are secured to futtocks 25, 26 and 27 respectively.

Ribs 28 and 29 converge at bracket 19 and are secured thereto. Their intermediate portions are secured to the body boat sheathing and their lower ends to futtocks 30 and 31. Longitudinally and rearwardly spaced from bracket 19 is a bracket 32, at which converge ribs 33, 34 and 35.

Immediately above bracket 18 and in connection with the latter through a framing strip 36 is an anchor bracket 37. Downwardly converging struts 38 and 39 secured at their upper ends to front and rear spars 17 and 40 are secured at their lower ends to bracket 37. A strut 41 is secured at its upper end to spar 40 adjacent the point of attachment thereto of strut 39 and at its lower end to bracket 32. The point of attachment of strut 38 to spar 17 is immediately adjacent the point of attachment thereto of upright 16. Only the right hand struts 38 and 39 appear in Figure 1.

From the above description, it will be apparent that lifting stresses of plane 6 will be transmitted through struts 38, 39 and strip 36 to ribs 20, 21, 22 and 23 to be distributed over a considerable portion of the body boat and the stresses transmitted through strut 41 will be similarly distributed through ribs 33 and 35. Lifting stresses of lower wing 8 will be transmitted through anchor brackets 18 and 19 and distributed through the two series of ribs 20 to 23, 28 and 29.

When the amphibian is resting on the water the landing weight of the wings will be similarly distributed. Since when landing on the ground, the rod 14, its cooperating cylinder and upright 16, form a compression unit between wheel 12 and spar 14, the stresses in-

incident to landing will be distributed in the manner already described.

It will be understood that I do not limit myself to the exact arrangement illustrated, ⁵ but that my invention contemplates structure coming under the terms of the following claims.

What I claim is:

1. In an amphibian, a body boat, a plane ¹⁰ above said body boat, landing gear at one side of said body boat, a compression member connecting the landing gear with said plane, a strut attached at one end to the plane at the point of connection of said compression member and at its other end to the body boat, the body boat structure including a plurality of ribs upwardly convergent toward the end of said strut in connection with the body boat.

2. In an amphibian, a body boat, a plane ²⁰ above said body boat, a wing projecting laterally of the body boat beneath said plane, a strut extending from said plane to the body boat to the rear of said wing, and a pair of anchor brackets for the wing spaced longitudinally of the body boat, the body boat structure including a set of ribs converging upwardly to each of said brackets and secured thereto, and a third set of ribs converging upwardly to the point of attachment of ³⁰ said strut to the body boat and a landing gear supporting member fastened to said body boat adjacent the lower portion of a converging rib.

3. In an amphibian, a body boat, a plane ³⁵ above said body boat, a wing projecting laterally of the body boat beneath said plane, a strut extending from said plane to the body boat to the rear of said wing, and a pair of anchor brackets for the wing spaced longitudinally of the body boat, struts connecting the plane with the body boat adjacent and above said brackets, the body boat structure including a set of ribs converging upwardly to each of said brackets and secured thereto, ⁴⁰ and a third set of ribs converging upwardly to the point of attachment of said strut to the body boat, and a landing gear supporting member fastened to said body boat adjacent the lower portion of a converging rib.

4. In an aircraft, a hull, a plane above said hull, a lower wing projecting laterally of said hull, a strut connecting a portion of the hull to the rear of said wing with said plane, a pair of anchor brackets for the wing spaced longitudinally of the hull, ribs converging upwardly to each of said brackets and to the point of attachment of said strut to said hull. ⁵⁰

5. In an aircraft, a hull, a plane above said hull, a wing projecting laterally of the hull ⁶⁰ beneath said plane, fittings spaced longitudinally of said hull, struts extending from two of said fittings to the plane and the lower wing attached to a third fitting, means associated with said fittings for distributing the loads transmitted to the hull by said fittings. ⁶⁵

6. In an aircraft, a hull, a plane above said hull, a lower wing projecting laterally of the hull, fittings spaced longitudinally of the hull, two of the fittings adapted to serve as anchor brackets for the lower wing, a strut connecting a third fitting and the plane, a strut connecting the plane with the hull adjacent and above one of said fittings and means for distributing the load transmitted to the hull by said fittings. ⁷⁰

7. In an amphibian, a hull, landing gear, a plane above said hull adapted to support a motor and to receive and transmit shocks transmitted by the landing gear, fittings spaced longitudinally of the hull, struts connecting the fittings with the plane and means for distributing the load transmitted to the hull by said fittings. ⁷⁵

Signed at College Point, Long Island, in the county of Queens and State of New York ⁸⁰ this 2nd day of November A. D. 1929.
